Primary Examiner — Karen S Acker*Assistant Examiner* — Steven B Reinholdt, Jr.(74) *Attorney, Agent, or Firm* — Faegre Baker Daniels LLP(57) **CLAIM**

The ornamental design for a firearm-mounted optical device, as shown and described.

DESCRIPTION

FIG. 1 is a front perspective view of a firearm-mounted optical device illustrating our new design.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines and the areas surrounded by them illustrate portions of the firearm-mounted optical device that form no part of the claimed design.
